UNITED STATES PATENT OFFICE.

MELVILLE CLARK, OF CHICAGO, ILLINOIS, ASSIGNOR TO MELVILLE CLARK PIANO COMPANY, OF CHICAGO, ILLINOIS, A CORPORATION OF ILLINOIS.

GOVERNOR FOR AIR-MOTORS.

1,273,579.

Specification of Letters Patent.

Patented July 23, 1918.

Application filed September 13, 1917. Serial No. 191,109.

To all whom it may concern:

Be it known that I, MELVILLE CLARK, a citizen of the United States, residing at Chicago, in the county of Cook and State of Illinois, have invented new and useful Improvements in Governors for Air-Motors, of which the following is a specification, reference being had to the accompanying drawings, forming a part thereof.

10 The purpose of this invention is to provide an improved means for governing the operation of an air motor particularly when such motor is employed for driving the note-sheet-propelling means of an automatic piano player. It consists in the elements and features of construction shown and described as indicated by the claims.

In the drawings:

Figure 1 shows a front elevation of a portion of an air motor equipped with a governor embodying this invention.

Fig. 2 is a section at the line, 2-2, on Fig. 1.

Fig. 3 is a section at the line, 3-3, on Fig. 2.

Fig. 4 is a plan view of a modified form of governor.

Fig. 5 is a section at the line, 5-5, on Fig. 4.

30 Fig. 6 is a section at the line, 6-6, on Fig. 5.

Fig. 7 is a section at the line, 7-7, on Fig. 4.

In the drawings, A is a conventional representation of a portion of an air motor of familiar construction; B is a conventional representation of exhaust devices for operating the motor; C is an air pipe which leads from the exhaust devices to the motor by way of the governing devices hereinafter further described. In the form shown in Figs. 1 to 4 inclusive, the air connection from the exhaust devices of the motor comprises two chambers, 1 and 2, separated by 45 a valve seat, 3, having a port, 4, the air pipe, C, from the exhaust devices leading through the block, 6, to the chamber, 1, and the air pipe, C', from the motor, leading to the chamber, 2, through said block, 6. In the 50 chamber, 2, there is mounted for sliding on said valve seat and over said valve port, a slide valve, 7, whose stem extends out through one end of said chamber, and is operatively connected outside the chamber 55 with an actuator, consisting of a bar, 8,

mounted for sliding on the chamber, 1, connected with a tempo lever, 10, which is swung over the graduated tempo scale, 11, for operating the valve. The operating connection between the valve stem and said actuator, comprises the pneumatic, 12, having its fixed member mounted upon the actuator, which is for that purpose bent to extend upward as seen at 8^a, and the valve stem is connected to the moving wall of said pneumatic as seen at 12^a.

The bar, 8, is bent to extend horizontally over the pneumatic, and then downward and, at its lower end it is connected by a spring, 15, with the moving wall of the pneumatic, the spring being stretched by the collapse of the pneumatic and reacting to hold the pneumatic normally expanded. The pneumatic is connected by a tube, 16, with the exhaust devices, so that the exhaust tension produced in the exhaust devices and operating for other purposes in the automatic player, is experienced in said pneumatic with a tendency to collapse it against the resistance of the spring, 15.

With the construction shown and with variable exhaust tension it will be seen that in whatever position the operator may set the tempo valve, 7, for regulating the speed of playing, the valve and expansion of the pneumatic, 12, according to the degree of exhaust tension produced in the exhaust devices; with the desired result, namely, that whereas a higher exhaust tension in the exhaust devices with a given adjustment of the tempo valve would yield a more rapid rate of action of motor and more rapid playing, thus defeating the accuracy of the control of speed by means of the tempo lever, the action of the pneumatic, collapsed more or less according to the degree of exhaust tension, operates to close the valve, 4, as the exhaust tension is increased, and to open it as the tension is lowered, thus preventing the change of speed which would otherwise result from the change of exhaust tension with a given adjustment of the tempo lever.

In the form shown in Figs. 5 to 7 inclusive the same result is obtained by means differing in this, that instead of having the tempo valve mounted for movement with respect to the actuator which is moved by the tempo lever, the valve seat is made movable with respect to the valve, and said valve seat is moved by the pneumatic instead

of the valve being moved with respect to the actuator as in the preceding figures. In said Figs. 5 to 7 inclusive, the parts identical, substantially, with the preceding figures, 5 are similarly indicated; the valve seat, however, consisting of a part, 3^a, which is mounted movably with respect to the partition, 3, of which it forms a part, has a stem, 17, which extends out from the end of the chamber and is connected at 12^a to the moving wall, of the pneumatic, 12; and the spring, 15, connected with the pneumatic for holding it normally expanded is attached to a bracket, 18, fixed with respect to the entire 15 casing which comprises the chambers, 1 and 2.

I claim:

1. A governor for an exhaust-operated air motor comprising a tempo valve which 20 controls the communication of the motor with the exhaust devices, and a seat for the same having a port which the valve controls, the valve and seat being relatively movable for varying the extent to which the valve covers 25 the port; tempo-controlling means for actuating one of said parts,—valve and seat,—a pneumatic and duct connection therefrom to the exhaust devices independent of the exhaust device connection with the motor, the 30 movable wall of the pneumatic being operatively connected with one of said two rela-

tively movable parts,—valve and seat,—for moving the same according to the degree of the collapse of the pneumatic, and a spring which resists such collapse. 35

2. In a construction such as set out in claim 1, the pneumatic-actuated one of said two relatively movable parts being the valve seat.

3. In a construction such as set out in 40 claim 1, one of said two relatively movable parts being connected for actuation by the tempo-controlling means, and the other being connected for actuation by said pneumatic. 45

4. A governor for an exhaust-operated air motor comprising a duct or passage for connecting the exhaust devices with the motor and two means for controlling the flow of air through said duct connections; a pneumatic having independent connection with the exhaust devices; mechanical connections from the pneumatic for operating one of said controlling means, and mechanical connections independent of said pneumatic for 55 operating the other of said controlling means.

In testimony whereof, I have hereunto set my hand at Chicago, Illinois, this 7th day of September, 1917.

MELVILLE CLARK.
